GAME BOARD WITH MARKED GAME PIECES

Fred J. Lucassen, San Francisco, Calif.

Application January 3, 1950, Serial No. 136,437

12 Claims. (Cl. 273—131)

1

This invention relates to new and useful improvements in game apparatus.

The present invention relates to a game which may be played by 2, 3, or 4 players. It employs a board marked off into squares and gamepieces which may be placed over the squares. Some of the gamepieces have point values, and when a player succeeds in moving such a gamepiece off the board he earns points, the first players reaching a predetermined number of points winning the game. Other gamepieces are provided with indicia which designate the gamepieces as moveable toward or away from the player, as hereinafter appears.

The equipment necessary to play the game comprises the board and playing pieces. Thus the equipment is relatively inexpensive. The game is highly entertaining in that it requires concentration and ability to predict the probable future moves of one's opponent, whereas chance does not enter into the result of the game.

In the drawings:

Fig. 1 is a plan of the board used in playing the game.

Fig. 2 is a plan showing the playing pieces in position on said board.

Fig. 3 is a perspective of a playing piece.

Fig. 4 is a diagrammatic view showing the commencement of a typical first move in a game.

Fig. 5 is a diagrammatic view showing the completion of the move shown in Fig. 4.

Fig. 6 is a diagrammatic view showing the commencement of a typical second move in a game.

Fig. 7 is a diagrammatic view showing the completion of the move shown in Fig. 6.

The game board 10 used in this invention has a square, flat playing surface divided into sixteen squares, four squares in each row and column. The squares are marked with suitable indicia to indicate the proper position for the gamepieces 11 at the commencement of the game. The gamepieces 11 are substantially square blocks of the same size as the squares of the game board and have flat bottom surfaces so that they may be easily slid over the surface of the game board. For convenience in moving the gamepieces, they may be beveled or recessed as shown by reference numeral 12 around the top edge so that they are higher in the center of the top surface than at the edges of the top surface. Thereby an individual gamepiece may more readily be picked up, or drawn toward or away from the player, all of which manipulations are required in the progress of the game.

Seventeen gamepieces—i. e., one more than

2

the number of squares on the board are used in playing the game. Six of the gamepieces are painted red (13), five are painted green (14), two are painted half red and half green (15), and the four remaining gamepieces (16, 17, 18) are provided with numerical symbols designating point values which may be plus or minus and thus count for or against the player. The board is initially set up as indicated in Fig. 2 and there is one additional red piece 13 which is handed to the player who commences the game. The player commencing the game takes the red gamepiece 13 and places it at the far end of any of the columns of gamepieces facing him and then bodily moves all the gamepieces in said column toward him one square. This manipulation pushes one gamepiece off the playing area of the board and said gamepiece is handed to the second player. If the gamepiece which is forced off the board by the first player is red (13), the second player must position the red gamepiece 13 at the far end of any of the four columns facing him and then push all the gamepieces in that column toward him one square. If, on the other hand, the gamepiece handed the second player is green (14), he must place the green gamepiece 14 at the near end of any of the four columns and push all the gamepieces in said column one square away from him. If the gamepiece handed to the second player is both red-and-green (15), the second player may employ it either as a red gamepiece or a green gamepiece, or, in other words, he may move any of the columns toward or away from him one square at his option. The game continues with each player receiving a red (13) or green (14) or two-colored (15) gamepiece and using it to move any of the columns toward or away from him, depending upon the marking of said gamepiece.

The object of the game is to force positive value point pieces 16 or 17 off the playing area of the board and thus score points. Thus, if one of the players succeeds in pushing the 100-point piece 16 off the board he scores 100 points. If he succeeds in pushing the 75-point piece 17 off the board, he scores 75 points. If he succeeds in pushing one of the two-colored point pieces 15 off the board he scores 25 points. If, on the other hand, the progress of the game requires that he push one of the negative value point pieces 18 off the board, the value of said point piece 18 counts against him.

When a point piece 16, 17 or 18 is forced off the board, it is restored to its initial position at the commencement of the game. If this necessi-

tates removal of a red (13), green (14), or two-colored piece (15) which had immediately theretofore occupied the original position of the point piece, such red, green or two-colored piece is handed to the next player in turn. If a different point piece 16, 17 or 18 happens to occupy the initial position of the returned point piece, the former must in turn be restored to its own original position, and this may require several successive moves until a red 13 or green 14 or two-colored piece 15 is liberated to be used by the next player in turn. A total winning score is determined at the beginning of the game and the first player to reach this score wins.

The gameboard is painted with the original positions of the gamepieces designated thereon as shown in Fig. 1. The surface of the board 10 is marked with red and green arrows 25 and 26 so as to remind the players in which direction the colored gamepieces 13 and 14 must be moved. Further, to facilitate keeping score, the game board may be provided with a number of markers or beads 31 strung along a wire 32, each marker 31 representing a given number of points. The board is cut out in a rectangular section 33 and the wire 32 on which the markers 31 are strung is embedded adjacent said cut-out portion. Thus, the markers 31 may be slid along the wire 32 as a player scores points to indicate his total.

If two players play the game they sit at adjoining sides rather than opposite one another. When four players play, they play as partners and alternate around the board in making plays. When three players play, two are partners and the other player opposes the partnership. It will be observed that opponents move the playing pieces in transverse directions.

In Figs. 4 to 7, inclusive, are shown diagrammatically the first two moves in a typical game. In Fig. 4 the first player has positioned the red gamepiece 13 at the far end of the second column of playing pieces facing him on the playing board and is ready to pull the gamepiece 13 toward him along with the four gamepieces in said column. In Fig. 5 is shown the completion of the move initiated in Fig. 4. It will be seen that said first move has liberated a green playing piece 14 from the playing area of the board. The liberated green playing piece 14 is, accordingly, handed to the second player, who sits on the first player's left. In Fig. 6 is shown a typical initial move by the second player. It will be noted that since the playing piece handed to him is green (14) instead of red (13) he has placed the green piece 14 at the near end of the third column of playing pieces facing him on the playing board and is prepared to push the green playing piece 14 and the four playing pieces in the selected column away from him one square. In Fig. 7 is shown the completion of the move initiated in Fig. 6. This move has liberated from the playing area of the board a green playing piece 14 which will be handed to the next player in turn.

It will be understood that although in the figures, descriptions and accompanying drawings the board 10 has been divided into sixteen squares and there are seventeen gamepieces 11, the number of squares and gamepieces may be varied. Thus, a board having nine squares and ten gamepieces might be used, or a board having twenty-five squares and twenty-six gamepieces might be used as desired. The number of pieces assigned scoring values is also a matter of discretion and

the use of two-colored pieces 15 and the assignment of scoring value thereto is also optional.

Although I have described my invention in some detail by way of illustration and example for purposes of clarity of understanding, it is understood that certain changes and modifications may be made therein without departing from the spirit of the invention or scope of the appended claims.

I claim:

1. A board game apparatus comprising a board having a playing area divided in aligned rows and columns of squares of equal size, and a plurality of flat-bottomed, square playing pieces dimensioned to be placed to overlie said squares and to be slid over the playing area, the total number of said pieces being one greater than the number of squares, each of said pieces being dimensioned to substantially occupy one square, each of said pieces bearing an indicium, a first indicium on at least one piece indicating scoring value, second indicia on a plurality of pieces indicating required movement of a column of pieces in a direction toward the player, and third indicia on a plurality of pieces indicating required movement of a column of pieces in a direction away from the player.

2. A board game apparatus comprising a board having a playing area divided in aligned rows and columns of squares of equal size, and a plurality of flat-bottomed, square playing pieces dimensioned to be placed to overlie said squares and to be slid over the playing area, the total number of said pieces being one greater than the number of squares, each of said pieces being dimensioned to substantially occupy one square, each of said pieces bearing an indicium, first indicia on at least one piece indicating scoring value, second indicia on a plurality of pieces indicating required movement of a column of pieces in a direction toward the player, and third indicia on a plurality of pieces indicating required movement of a column of pieces in a direction away from the player, and fourth indicia on a plurality of pieces indicating movement of a column of pieces either toward or away from the player at his option.

3. A board game as defined in claim 2 in which said first indicia are displayed on a plurality of pieces and some of said first indicia indicate plus scoring value and others minus scoring value.

4. A board game as defined in claim 2 in which said first indicia are displayed on a plurality of pieces and some of said first indicia indicate plus scoring value and others minus scoring value, and wherein the indicated values of said first indicia vary in amounts.

5. A board game as defined in claim 2 and wherein said fourth indicia indicate scoring value.

6. A board game as defined in claim 2 and wherein the number of pieces having second indicia and the number of pieces having third indicia differ by one.

7. A board game apparatus comprising a board having a flat square playing area divided into aligned rows and columns of squares of equal size and a plurality of playing pieces adapted to be placed overlying said squares and to be slid over the surface of the playing area, the total number of said pieces being one greater than the number of squares, each of said pieces being dimensioned substantially to occupy one square, each of said pieces bearing an indicium, first indicia on a plurality of pieces indicating plus scoring value, second indicia on a plurality of

pieces indicating a minus scoring value, third indicia on a plurality of pieces indicating required movement of a column of pieces in a direction toward the player, fourth indicia on a plurality of pieces indicating required movement of a column of pieces in a direction away from the player, the number of pieces having third indicia and the number of pieces having fourth indicia differing by one, and fifth indicia on a plurality of pieces indicating movement of a column of pieces either toward or away from the player and also indicating scoring value.

8. A game as defined in claim 7 and wherein said board is marked with the positions of said pieces at the beginning of the game, the markings on said board corresponding to the markings of the overlying pieces at the start of the game.

9. A board game comprising a board having a flat square playing area divided into sixteen equal squares, and seventeen playing pieces each of said pieces having at least one flat face dimensioned to overlie one of said squares, two of said pieces having positive scoring value indicia, two of said pieces having negative scoring value indicia, six of said pieces having indicia indicating that they must be moved in one direction relative to the player, five of said pieces having indicia indicating that they must be moved in the opposite direction relative to the player, and two of said pieces having positive scoring value indicia and indicia indicating that they may be moved either toward or away from the player at his option.

10. A game comprising a board having a given number of player stations, said board having a flat playing surface provided with a predetermined number of gamepiece receiving squares, said squares arranged in columns and rows, each column and row comprising an equal number of squares, and gamepieces exceeding in number by one piece the number of squares provided on said board, said gamepieces each having a flat board contacting surface and being dimensioned to overlie one of said squares and comprising at least one value piece having value indicia thereupon and two sets of player pieces having identifiable indicia thereupon, one set including one player piece more than the other set, said player pieces being of substantially equal size and

formed so that when one piece is moved slidably against another piece the piece moved against moves in a substantially straight path.

11. A game comprising a board having a given number of player stations, said board having a flat playing surface provided with a predetermined number of gamepiece receiving squares, said squares arranged in columns and rows, each column and row comprising an equal number of squares and gamepieces exceeding in number by one piece the number of squares provided on said board, said gamepieces each having a flat board contact surface and being dimensioned to overlie one of said squares and comprising at least one value piece having value indicia thereupon and three sets of player pieces having identifiable indicia thereupon, the first of said sets having one player piece more than the second of said sets, said player piece being of substantially equal size and formed so that when one piece is moved slidably against another piece the piece moved against moves in a substantially straight path.

12. A game comprising a board having a given number of player stations, said board having a flat playing surface provided with a predetermined number of gamepiece receiving squares, said squares arranged in columns and rows, each column and row comprising an equal number of squares, and a plurality of gamepieces, said gamepieces each having a flat board contacting surface and dimensioned to overlie one of said squares and comprising at least one value piece having value indicia thereupon and two sets of player pieces having identifiable indicia thereupon, said player pieces being of substantially equal size and formed so that when one piece is moved slidably against another piece the piece moved against moves in a substantially straight path.
